UNITED STATES PATENT OFFICE.

AUGUST F. OSTERLIND, OF ST. PAUL, MINNESOTA.

PLATE-MOUNTING EQUIPMENT.

Application filed January 7, 1922. Serial No. 527,646.

To all whom it may concern:

Be it known that I, AUGUST F. OSTERLIND, a subject of the King of Sweden, residing at St. Paul, in the county of Ramsey and State 5 of Minnesota, U. S. A., have invented new and useful Improvements in Plate-Mounting Equipments, of which the following is a specification.

It is my object to simplify and cheapen 10 plate mounting equipment for printing presses by providing peculiarly formed steel bars which are used for the base as well as furniture in printer's forms.

As is well known, the bases and furniture 15 in common use are cast iron or wooden blocks or lead plates. This equipment is unsatisfactory in that the wood soon becomes distorted by moisture and wear; the cast iron furniture and bases are extremely expensive 20 because each rectangular block must be machined on all six faces, and the lead furniture and bases soon become worn because of the softness of the material and the frequent cleaning which is necessary. This cleaning 25 gradually removes the surface metal until the plate must be discarded because it is undersize. The metal equipment in common use and especially that made of lead has the additional fault of being very heavy so that 30 the speed of the printing presses is greatly reduced. It is my purpose to obviate these defects and to reduce the amount of time and labor required in mounting the equipment.

35 My invention in its preferred embodiment consists of rolled and cold drawn steel I beams or bars of various widths and uniform standard height (0.759 inch), cut in the desired lengths to form bases and furniture of 40 the necessary sizes. In manufacturing my improved equipment steel bars are first hot rolled to approximately or slightly over finished size; are then pickled in a suitable brine to remove the scale and the like and are 45 finally cold drawn to the exact finished size. By this process the equipment is produced at a greatly reduced cost as compared with present equipment and the finished bars are more accurate and uniform. Further, the 50 peculiar form and rigidity of the bars make them adapted for use as furniture, where the bending force is great, as well as strong enough to withstand great compressing strains as when they are used for a base. 55 It will be readily understood that by making the bars of I beam form in cross section

the weight is reduced to a minimum without sacrificing strength.

In the accompanying drawings, which illustrate the best form of my device at 60 present known to me, Fig. 1 is a plan view of a chase assembled to receive the plates, said plates being indicated in dotted lines; Fig. 2 is a section taken on the line 2--2 of Fig. 1, a plate being shown in place on the 65 base; Fig. 3 shows end views of three of the component I beams and Fig. 4 is a detail perspective view of one of the I beams or bars.

Referring to the drawings, plates 10 and 70 11 are mounted in the usual chase 12 upon the bases 13, being held in place by suitable hooks 14. The chase 12 is filled in by furniture indicated at 15 and 16, said furniture being held within the chase 12 in the usual manner by quoins 17. The several elements of 75 the bases 13 and furniture 15 and 16 consist of a series of I beams or bars 18 of various lengths and widths but of uniform thickness. The bars 18 are formed with vertical webs 80 18^a and horizontal, identical flanges 18^b and 18^c on their upper and lower extremities, respectively. The end surfaces of the flanges 18^b and 18^c are vertical so that they will bear uniformly one against another when assembled. As will be readily understood the bars 18 are assembled by placing their flanges 18^c on the imposing stone so that the flanges 18^b present a plain surface upon which the plates are mounted when said bars are used as a 90 base. The furniture 16 is laid out in hollow rectangles of the desired size to fill the chase. When laid out as shown in Fig. 1 with the bars 18 in parallel or vertical relation to each other the quoins 17 hold them securely in place. The bases 13, as clearly 95 shown in Figs. 1 and 2, comprise a series of the I beams 18 laid in parallel relation on an imposing stone or surface 19.

I prefer to build up the base and furniture from a number of I beams, like those illustrated in Fig. 3, viz., of one inch, one-half inch and one-third inch width so that plates of any desired width in picas may be mounted. The length of the several I 100 beams differ from each other by multiples of one inch.

Having described my invention what I claim as new and desire to protect by Letters Patent is:

1. In plate mounting equipment, a base comprising, a plurality of bars of uniform

height and varying superficial area adapted to be held in parallel relation to each other in a printer's form, each of said bars being formed with a web and identical flanges projecting at right angles to said web.

2. In plate mounting equipment, bases and furniture both comprising, a plurality of bars of uniform height and varying length adapted to be held in parallel and rectangular relation to each other in a printer's form, each of said bars being formed with a web and identical flanges projecting at right angles to said web.

3. In plate mounting equipment, bases and furniture both comprising, a plurality of bars of uniform height and varying superficial area adapted to be held in parallel and rectangular relation to each other in a

printer's form, each of said bars being formed with a vertical web and identical flanges projecting at right angles to said web.

4. In plate mounting equipment, bases comprising, a plurality of I beams of uniform height and varying flange area adapted to be held in parallel and rectangular relation to each other in a printer's form.

5. In plate mounting equipment bases comprising, a plurality of cold drawn steel I beams of uniform height and varying flange area adapted to be held in parallel and rectangular relation to each other in a printer's form.

In testimony whereof, I have hereunto signed my name to this specification.

AUGUST F. OSTERLIND.
